CLAIM

The ornamental design for the diaper bag or baby stroller basket organizer, as shown and described.

DESCRIPTION

FIG. 1 is a perspective view of the diaper bag or baby stroller basket organizer;

FIG. 2 is a top plan view of the diaper bag or baby stroller basket organizer;

FIG. 3 is a front elevational view of the diaper bag or baby stroller basket organizer;

FIG. 4 is a bottom plan view of the diaper bag or baby stroller basket organizer;

FIG. 5 is a left side elevational view of the diaper bag or baby stroller basket organizer;

FIG. 6 is a right side elevational view of the diaper bag or baby stroller basket organizer; and,

FIG. 7 is a rear elevational view of the diaper bag or baby stroller basket organizer.

The broken line showing of environment in FIG. 1 is for illustrative purposes only and forms no part of the claimed design.
